ELECTRICAL CIRCUIT BREAKER

Olav Maseng, Detroit, Mich.

Original application October 22, 1934, Serial No. 749,330, now Patent No. 2,080,178, dated May 11, 1937. Divided and this application April 26, 1937, Serial No. 138,913

8 Claims. (Cl. 200—148)

This invention relates to electrical circuit breakers and is a division of my U. S. Letters Patent No. 2,080,178, issued May 11, 1937, and an object of this invention is to provide an improved means for opening an electric circuit while current is flowing therein and including a means for reducing the arcing at the terminals.

It has previously been the practice to provide a circuit breaker for the said purpose in which a liquid is used to enclose the terminals as for instance as disclosed in the U. S. patent to T. T. Greenwood, No. 1,825,228 or Herbert Pearce, Patent No. 1,841,147.

It is the present practice with circuit breakers to utilize insulating liquids or gases of high dielectric strength as the means for extinguishing or interrupting the arc. Such prior characters of interrupting devices are costly in character and large in size and introduce a fire and explosion hazard. The object of this invention is to avoid the use of such prior means and provide a circuit breaker differing materially from such prior art in that self-generated arc gases are of low dielectric strength and are utilized under high pressure to provide an extinguishing blast across the co-acting surfaces of the arc terminals.

The invention distinguishes from previously known arc gas circuit breakers (such for instance as R. H. Read Patent No. 730,704) in that by means of a novel arrangement of the parts, the initially produced arc gases are passed through a restricted passageway of such form as to effect a partial deionization or cooling, cleaning and guiding of the gas blast.

It is further an object and feature of the invention to provide a circuit breaker which includes a series of contacts in such relation that the breaking of one produces a gas which is subsequently utilized to quench a second arc drawn in series with the first.

A further and major object of the invention resides in the provision of an intermediate contact element positioned between the main contacts of the circuit breaker wherein by first separating a main contact and the intermediate contact, an arc is drawn and thereafter the intermediate contact separated from the other main contact by pressure of gases produced by the first arc which flow under pressure between the said intermediate and second main contact.

These several objects and novel features of the invention are hereinafter more fully described and claimed, and an embodiment of the invention is shown in preferred form in the accompanying drawing in which—

Fig. 1 is a longitudinal section of a convenient form of a circuit breaker embodying my invention.

Fig. 2 is a partial sectional view showing the contact elements in the position assumed upon the producing of the initial arc and the resultant gases.

Fig. 3 is a similar view showing the contacts fully open under a condition in which the gases first produced are discharged to atmosphere.

Fig. 4 is a similar view showing an alternative form of intermediate contact element.

Fig. 5 is a view of another convenient structural form of contact elements involving my invention.

Fig. 6 is an end view of a bushing supporting one of the terminals.

Fig. 7 shows an alternative arrangement of one of the main contact elements.

The preferred form of my improved circuit breaker as shown in Fig. 1, comprises a body 11 of insulating material. The specific construction of this body may be varied to suit different types of installation. The body has a bore 11' which opens through one end thereof and is closed by a threaded plug 20 with which is associated a packing means 20' of any desired character, preferably cementitious, between the plug and the body to seal the bore 11' at that end. Within the bore in the construction shown is a hollow movable main electrode or contact member 12 attached at its outer end in any convenient manner to an operating rod 13 which is movable longitudinally of the axis of the contact 12 by any approved means not here shown. The contact 12 has an external shoulder 12' which limits the withdrawal movement of the contact element as will be understood from Fig. 3 wherein, upon withdrawal to full extent, a shoulder engages the packing 20' or base of the plug through which the electrode extends. Within the contact 12 is the base of an intermediate contact or electrode 16 which has a tapered base 30 for contact with the correspondingly tapered end of the contact 12 as indicated in the position of the parts shown in Fig. 1. To this intermediate contact 16 is secured an insulating body 17, the outer free end of which is formed with a collar 21 somewhat greater in diameter than the body. This collar 21 is engaged by the internal shoulder 31 of the element 12 when it is withdrawn to the position shown in Fig. 2.

The intermediate electrode 16 has a cone-like terminal portion 32 and as shown in Fig. 1, this coned end 32 engages the cone shaped end 33 of

the hollow contact 14. This contact element 14 is mounted in a recess 34 in axial alignment with the chamber 11' and having a side outlet to atmosphere indicated at 35. The electrode or contact element 14 has an extension 19 with which one side 36 of the main circuit is connected while the other side 37 of the main circuit is connected to the contact 12 as diagrammatically shown in Fig. 1. There is a spring 15 engaging a base of the main contact 14 holding the same in the position shown, there being a slight movement of the contact 14 on the axis of the intermediate member and the other main contact 12 to insure contact.

15 In this fundamental form of the invention, it will therefore be realized that there is a main contact 12, a companion main contact 14 and an intermediate contact 16 in engagement with both the said main contacts when in the closed position shown in Fig. 1. The intermediate contact 16 is pressed to engagement with the contact 14 by means of a spring 18 in the hollow contact 12. Upon starting to open the circuit in this primary construction, the contact 12 is withdrawn by 20 means of the operating rod 13 and associated instrumentalities (not here shown) for causing said movement.

Upon initiating movement of the contact 12, the tapered edge thereof is separated from the 30 coned face 30 of the intermediate contact 16 which is in engagement with the main contact 14. This causes an arc and development of a high pressure gas in the chamber 11' which, during this initial operation, remains closed. On further movement of the member 12 the shoulder 31 35 engages the enlarged portion 21 on the insulating member withdrawing the coned face 32 out of contact with the coned mouth 33 of the hollow contact 14. This permits the high pressure gas caused by the initial separation of the contacts 12 and 16 to pass through the narrow opening 40 between the portion 32 of the intermediate contact 16 and the coned mouth 33 of the main electrode 14 to atmosphere through the passageways 34 and 35. The gas is partially deionized 45 and cleaned by being forced against the wall of the bore or chamber 11' and narrow passage between the intermediate contact 16 and said wall. These gases are so guided as to pass over the 50 surfaces of the intermediate electrode 16 and the main electrode 14 in intimate contact therewith and tend to quench the incipient arc between these members and maintain a steady high pressure blast over the arc terminals until the circuit 55 is completely interrupted.

To insure separation of the contacts 16 and 14, the enlarged end portion 21 is provided for engagement with the shoulder 31 of the contact 12 whereby, prior to completion of movement of the operating rod in separating the contacts, the intermediate electrode or contact 16 is forcibly 60 separated from the contact 14. In fact the intermediate contact may be provided with a longer insulation as indicated at 17' in Fig. 4 so that 65 when the contact 12 reaches its limit of withdrawal movement, the enlarged portion 21 of the insulating element 17' will just be engaged by the shoulder 31 of the contact 12 whereby contact 16 remains in engagement with contact 14.

70 In the structure shown in Fig. 4, the final separation of the intermediate contact 16 and main contact 14 is produced when the pressure within the chamber reaches a value sufficient to move contact member 14 against the force of spring 75 15. In this latter case, as the pressure in the

chamber decreases, the intermediate end 16 may again assume the position shown in Fig. 4 without closing the circuit as the said electrode is supported in the main electrode 12 by the insulation rod or element 17'. 5

It will be noted that, for the proper functioning of the device, the housing should be reasonably pressure tight except for the opening provided in the contact 14 and also that a narrow passageway should be provided between the 10 member 16 and the inside wall of the housing for the purpose of maintaining the arcs in series and the deionizing and partial cleaning of the gases. The effectiveness of a gas blast for interrupting purposes is measured by the means 15 found to produce a relatively smooth flow over the contact surfaces and through the arc core and in the case of arc gases, it is essential that the blast in the first case should be relatively clear of metal particles and secondly, that the 20 temperature should be appreciably lowered. In the structure embodying my invention these effects are accomplished in an inexpensive and simple manner. The restricted passageway serves to cool the gases and trap metal particles, 25 while further the peripherically close association of the intermediate contact and the inside wall of the housing insures that the blast sweeps concentrically over the entire contact surfaces and longitudinally through the length of the arc core 30 during the entire opening stroke of the circuit breaker. Also, for various applications, it is obvious that the insulation supporting the terminals may be carried in a metal casing.

In Fig. 5 there is shown an alternative form 35 of construction of the intermediate contact element or electrode, it may have a body 111 formed with a central bore 112 and has a contact element 113 corresponding in general to the element 12 of Fig. 1 and likewise movable in the bore 112. 40 In this construction, the bore 112 is enlarged at the right hand end as indicated at 114 and the outer end of the member 111 is threaded to receive a cap 40. Between the cap and the end of the body is the packing material 40' which 45 may be cementitious in character. The cap 40 has a flanged bushing or sleeve 39, the body of which extends into the bore 114. The hollow terminal 14 corresponds in all general respects to the terminal 14 of Fig. 1 and extends within the bushing 39 and has an enlarged inner end portion which slidably fits in the bore of the sleeve 39. Between the body of the element 14 and the sleeve is located a spring 115 which tends to move the contact element 14 to the left to the position shown. The terminal end of the bushing or sleeve 50 55 55 is notched at 39' for a purpose hereinafter stated.

The intermediate contact or electrode 161 has a central ring like portion or flange 162, a coned 60 forward end 163 for contacting the terminal 14, and a truncated cone shaped portion 164 on the opposite side which is engaged by the coned edge 165 of the movable terminal 113. This terminal 113, when moved to engagement with the coned 65 face 164 of the intermediate electrode 161, will force the electrode 161 and the contact element 14 to the right until the ring like flange portion 162 engages the notched end of the sleeve 39. When in this position, upon movement of 70 the element 113 to the left, the intermediate electrode 161 will follow the same until the flange 162 thereof engages the shoulder between the bores 112 and 114 by influence of the spring 115. As soon as this intermediate electrode 161 ceases 75

to follow the movable electrode 113, the first arc is drawn and gas pressure developed in the bore 112 which will force the electrode 161 and 114 to the right of the position shown until the flange 162 seats against the end of the sleeve 39. The gases may escape through the slots or notches 39' and the electrode 14, under this pressure, will move outwardly and the gases pass to atmosphere through the hollow portion thereof.

10 This form of the invention functions equally as well as the previously described forms and it is to be noted that, in this form of the invention, the spring 115 is practically shielded from direct contact with the heated gases.

15 In Fig. 7 is shown an alternative arrangement of the electrode 14 which in all essential respects is the same as that shown in Fig. 1. The spring 151, however, is positioned between a shoulder 152 in the interior of the body and the outturned end of the electrode 14 which receives the coned end of the electrode 16. A packing ring 153 is positioned behind the outturned end of the element 14 and practically fitting the bore 11' and the spring 151 lies in the recess between the packing and the shoulder 152 and thus is shielded from direct contact with the heated gases passing through the interior of the member 14 to atmosphere.

20 In either of the forms of the invention, the interruption of the arc is produced by the quenching effect of the gases developed in the central chamber of the insulating body and it is believed evident that the structure may be varied in detail in adapting the circuit breaker for

25 various types of installation.

20 The housing 11 of Fig. 1 or 111 of Fig. 5 may be of any desired construction or form and the material utilized in the contact supporting parts may be varied in respect to gas generating and 30 arc resisting qualities, depending upon the duty and character of the circuit with which my circuit breaker is usable.

35 It is believed also evident from the foregoing, that the various features and objects of the invention are attained by the structure described, and that the breaker is comparatively small and compact in form and less expensive in construction than the usual circuit breakers of the same capacity utilizing insulating liquids such as hereinbefore referred to. It is also pointed out that various changes may be made in the form and structure of the parts without departing from the spirit and scope of the invention as set forth in the appended claims.

55 Having thus fully described my invention, its utility and mode of operation, what I claim and desire to secure by Letters Patent of the United States is—

1. In an electrical circuit breaker, an insulating housing having an air filled chamber, a pair of main contact members in said chamber forming the terminals of a circuit to be interrupted, an intermediate contact member movably supported in the chamber between the two main contact members, means for moving one of the main contact members from engagement with the intermediate contact member to thereby produce an arc and thereby provide gas under pressure within the housing, the other of the said main contact members mounted to permit movement by pressure of the arc gases generated within the housing and having a passageway to atmosphere normally closed by the intermediate contact member and opened by pressure developed by said arc produced gases whereby the

5 gases under pressure are discharged to atmosphere between the co-acting surfaces of the intermediate and apertured contact member to thereby quench the arc therebetween.

2. In an electrical circuit breaker, an insulating housing, a pair of axially aligned main contact members therein forming the terminals of a circuit to be interrupted, an intermediate contact member, means normally supporting the intermediate contact member in axial alignment 10 between the said main contact members, means for separating one of the main contact members from the intermediate contact member and the other of the main contact members being mounted to permit movement by pressure of the arc 15 gases generated within the housing, there being an opening to atmosphere normally closed by the intermediate contact member and opened by movement of the said movable contact member under pressure of the gases whereby the co-acting surfaces of the intermediate and last named main contact member are swept by the 20 gases in passage through the opening to atmosphere.

3. In an electric circuit breaker, a housing of 25 insulating material having a chamber extending longitudinally thereof, a pair of main contact elements forming terminals of a circuit to be interrupted, an intermediate contact member positioned in the arc path between the said contact elements, means for moving one of the main contacts from engagement with the intermediate member to thereby draw an arc and produce high pressure gases in the chamber, the other main contact having an aperture there- 30 through to atmosphere normally closed by the intermediate member, a spring normally tending to force the apertured main contact member to engagement with the intermediate member, the arrangement providing that pressure 35 developed by the gases separates the intermediate and the apertured contact members, whereby the co-acting surfaces of the two said members are swept by the gases in passing to atmosphere through the said apertured contact member.

4. A circuit breaker comprising an insulating, air filled, housing, a plurality of contact members enclosed therewithin, means for operating the members in such manner that at least two 50 of the members are separated whereby an arc is drawn therebetween generating a high pressure gas within the housing, another of said contact members being mounted to permit movement whereby the generated gases tend to separate 55 the remaining engaged contact members, said housing being opened to a flow of gases therefrom by separation of the said last named contact members whereby the co-acting surfaces thereof are swept by the said gases and the 60 arc extinguished.

5. A circuit breaker comprising a housing having a central bore and a counter-bore of greater diameter opening through one end, a main contact member movably supported in the said 65 bore, a second movable main contact member, a cap member having an aperture through which the said member extends and is slidably, a flanged sleeve secured in place with the flange thereof between the cap and the end of the housing and 70 with the cylindrical portion extending into the counter-bore, said second main contact having an aperture therethrough and an enlarged end portion riding approximately in contact with the inner wall of the sleeve, a spring between the 75

said terminal end of the said second contact and the cap tending to move the said contact member inwardly of the recess, an intermediate member loosely mounted in the bottom of the said 5 counter-bore and having a flange seating on the wall at the bottom of the counter-bore and having a cone shaped end engaging the inner end of the last named main contact to close the aperture therein and a coned portion on the 10 opposite side of the flange for engagement with a coned face provided on the first contact member, the said flange of the intermediate member being movable between the end of the sleeve and the said bottom of the counter-bore under 15 influence of pressure of gases generated on movement of the first named main contact, the end of the sleeve having notches therein permitting gases generated by the initial arc to pass through the slots and exert separating pressure between 20 the intermediate electrode and the second main contact thereby separating the contacts and permitting flow of the gases between the co-acting surfaces of the said intermediate and apertured contact member to quench the arc.

25 6. A circuit breaker comprising an insulating housing, a movable main contact member and a second main contact member extending through the housing wall and having an aperture therethrough, an intermediate contact member having 30 a central portion with a periphery in close relation with the inside wall of the housing thereby providing a restricted, substantially cylindrical passageway between the said main contact members within the housing, the said central portion having a contiguous cone-shaped 35 end normally closing the said apertured main contact member, means for separating the contact members in such a manner that arc gases are first produced between the said movable and intermediate contact members whereby, upon 40 subsequent separation of the said intermediate and apertured contact members, the said arc gases are forced to pass through the said restricted passageway thereby being guided concentrically and intimately over the entire surface

of the said contiguous cone-shaped end of the intermediate contact member and subsequently axially through the entire length of the arc drawn between the said intermediate and apertured contact members.

7. In an air circuit breaker, a housing, a separable contact structure formed of several members therewithin, one of the contact members extending through the housing wall and having an aperture therethrough, a second contact member 10 having a portion in peripherally close association with the inside wall of the housing thereby providing a restricted passageway, the said portion of the second member having a contiguous contact end normally closing the aperture in the first named contact member whereby, upon separation, the arc gases produced between the other members of the contact structure are forced to pass through the said restricted 15 passageway thereby being cooled and cleaned 20 and subsequently guided concentrically and intimately over the entire surface of the said contiguous contact end and axially through the entire length of the arc drawn between the said second contact member and the contact member 25 having the aperture.

8. In an air circuit breaker, a housing having an opening, a separable contact structure within the housing comprising more than two contact members, an intermediate member of the 30 said contact structure having a central portion in peripherally close association with the inside wall of the housing thereby providing a restricted passageway, the said central portion having a contiguous contact portion, the arrangement providing that, upon separation of the contact structures, the arc gases produced in the housing are caused to pass through the restricted passageway thereby being cooled, cleaned, and guided to sweep concentrically about and in contact with the entire surface of the said contiguous contact portion and subsequently pass axially through the length of the drawn arc to said 35 opening of the housing.

OLAV MASENG.
